UNITED STATES PATENT OFFICE.

ALBON H. BAILEY, OF SOMERVILLE, MASSACHUSETTS.

DESIGN FOR TYPE-CASES.

Specification forming part of Design No. 5,728, dated March 26, 1872.

SPECIFICATION.

I, ALBON H. BAILEY, of Somerville, in the county of Middlesex and Commonwealth of Massachusetts, have invented and produced a new and original Design for Type-Cases for the use of Printers, of which the following is a specification:

My design relates to the arrangement of combination-type in cases, together with types of single letters, such as are now used. By combination-type I mean type containing those syllables and combinations of letters most commonly used. These combination-types I arrange as shown in the design, the object being to place those types most commonly used the nearest to the compositor, so as to be taken

from the case with the least trouble to him, and those less commonly used proportionally further distant.

My design is fully represented in the accompanying photographic illustration, to which reference is made, and in which the upper part represents the "upper case," and the lower part the "lower case."

I claim as my invention—

The design for upper and lower cases of printers' types, as shown in the accompanying illustration.

ALBON H. BAILEY.

Witnesses:

WM. H. BAILEY,
CHAS. C. DREW.
